UNITED STATES PATENT OFFICE.

GEORGE F. HENSEL, OF PHILADELPHIA, PENNSYLVANIA.

DESIGN FOR A FRINGE.

SPECIFICATION forming part of Design No. 16,724, dated June 8, 1886.

Application filed March 15, 1886. Serial No. 195,337. Term of patent 7 years.

To all whom it may concern:

Be it known that I, GEORGE F. HENSEL, a citizen of the United States, residing in Philadelphia, Pennsylvania, have invented a certain new and original Design for Ornamental Fringe, of which the following is a specification.

My design for a fringe is fully shown in the accompanying drawings, Figures 1, 2, and 3 of which represent variations in the detail of design, but all embody its main or distinguishing features, Fig. 4 being an enlarged view illustrating more clearly than the other figures the essential features of the design.

15 The design relates to the heading A, the fringing-threads, which project beyond the heading, being either looped or free at the ends, as desired.

The design comprises the upper and lower close bands, a b, and a central open-work band, d, which forms the leading feature of the design. This band has cross-pillars x and longitudinal bar or bars y, each of the latter consisting of bands w w', the band w passing across and concealing part of the face of each pillar x, and the band w' passing behind and being concealed by each pillar, but concealing the face-band w between the pillars, as clearly shown in the enlarged view,

Fig. 4, the pillars being contracted in width 30 where the bands cross the same. The cross-pillars are preferably of such strands that they present a solid effect, the individual strands of which the pillars are composed not being noticeable.

35 The number of longitudinal bars and the character of the cross-pillars may be varied without departing from the essential features of the design.

I claim—

40 The within-described design for a fringe-heading, said design consisting of upper and lower close bands and an intervening open work band having cross-pillars x and longitudinal bands w w', the band w concealing a portion of the face of each pillar, and the band w' being concealed by said pillars, but concealing the face-band w between the pillars, each pillar being contracted where the bands cross the same, all substantially as described and shown.

45 In testimony whereof I have signed my name to this specification in the presence of two subscribing witnesses.

GEORGE F. HENSEL.
